HEATING SYSTEM

Charles Meyer and Joseph A. Meyer,
Brooklyn, N. Y.

Application September 15, 1938, Serial No. 230,150

3 Claims. (Cl. 219—38)

This invention relates to a heating system or means for the water within the jacket of an internal combustion engine or any equivalent, which is designed to automatically operate to heat the water upon lowering of the temperature to a predetermined degree, in order to avoid freezing of the water in such jacket and make easy the starting of the motor.

A further object is to provide a novel construction which is readily controllable to govern the degree of heat employed.

It is further aimed to provide a structure which may be built as a unit and constitute an attachment as well as being capable of installation in automobiles or the like initially.

The more specific objects and advantages will become apparent from a consideration of the description following taken in connection with the accompanying drawings illustrating an operative embodiment.

In said drawings:

Figure 1 is a view in side elevation, showing our improvements applied to an automobile engine;

Figure 2 is an enlarged vertical section taken substantially on the line 2—2 of Figure 1;

Figure 3 is a fragmentary view, on a larger scale, showing the control of the improved device;

Figure 4 is a view looking toward the interior of the control member;

Figure 5 is a diagrammatic view showing the parts in position to give one degree of heat;

Figure 6 is a view similar to Figure 5 showing the parts in position to heat to a different temperature; and

Figure 7 is a view partly in plan and partly in horizontal section of the heater or boiler.

Referring specifically to the drawings wherein like reference characters designate like or similar parts, an internal combustion engine of conventional form is shown at 10 in association with its radiator 11, such engine having a conventional water cooling system.

Our improvements include a water container or boiler 12 connected at its top by means of a pipe 13 to the water jacket of the engine 10 and connected at its base by means of a pipe 14, with the communicating pipe or conduit 15 between the radiator, adjacent the base thereof, and the water jacket of the engine 10.

Our improvements include a mounting plate 16 preferably of suitable insulation which is attached to the engine 10. Such plate or support 16 mounts a plate or supporting ring 17, which

in turn supports the aforesaid water container or boiler 12.

Said boiler 12 is U-shaped in vertical section and it has a large recess or space 18 rising from its lower end in which is located a suitable core 19, of any suitable insulation, about which, in spiral grooves 20, electric heating elements or resistant means 21 are wound and disposed, adapted to be energised to heat the water within the container or boiler 12, which being heated, 10 will serve to circulate the water throughout the cooling system or jacket of the engine 10 and radiator 11, to avoid freezing of the water, as when the engine is idle, either on the street, in a garage or elsewhere.

Said heating elements or resistant means at 21 include three resistant elements 22, 23 and 24. Resistant element 22 is connected to a contact or conductor plate 25 and through a conductor 26 is also connected to a conductor plate 27. Said conductor plate 27 has a pair of conductors 28 and 29, connected thereto and to the coils 23 and 24. Said coils or resistants 23 and 24 are bridged by a conductor 30 which is connected to a conductor plate at 31. Said conductors or contacts 25, 27 and 31 respectively are engaged with clip conductors 32, 33 and 34, bolted or otherwise fastened to the insulating support 16 as at 35. Said contacts or conductors 25, 27 and 31 may be bolted or otherwise fastened as at 36 in a bar 30 or dependent 37 integral with the core of molded insulation or the like 19.

A suitable control member is provided at 38 in the form of a lever and made of suitable insulation, the same being pivoted as by means of a bolt 39 to the support 16. Said support 16 carries a receptacle 40, as best shown in Figure 6, which may be engaged by a separable plug connected at any suitable source of electric current, and of any desired voltage. The source may be 40 the electric battery of the automobile having the internal combustion engine 10, or it may be a house lighting supply or otherwise. Obviously the coils must be wound for the desired voltage. Conductors 41 and 42 lead from the receptacle 40 and the former is connected to a conductor ring or contact 43 fastened to the support 16. Conductor 42 includes a thermostat 44 of any desired type and leads to a disk conductor 45, surrounded by but spaced from the ring conductor 50 or contact 43. Said thermostat 44, as shown in Figure 1, is preferably connected in the pipe 14 and is adapted to automatically close with the lowering of the temperature of the water in the water jacket and cooling system, specifically the 55

water passing through the pipe 14, closing the thermostat to make the electric contact for passage of the current through the heating system for heating the water in the system and preventing freezing thereof. It is obvious that the thermostat is of such a construction and characteristics that it may be adjusted to automatically close at any desired predetermined temperature.

Reverting to the control lever 38, it has rigidly connected thereto, a ring contact 46 and a disk contact 47, in constant wiping engagement with the ring contact 46 and disk contact 45. Conductor fingers or contacts 48 extend from the ring conductor 46 and between the same a finger 49 or contact 49 extends from the disk 47, passing under the ring 46 at 50, or otherwise avoiding contact with such ring.

The control lever 38 preferably has an indicator 51 thereon coating with the numerals 1, 2 and 3, as shown in Figure 3, to indicate a position of the lever and which degree of heat the device is set for.

With the parts in the position of Figure 5, upon closing of the thermostat 44, the circuit will be closed giving the lowest degree of heat, such circuit including the contacts 46 and 47, contact 49 and right hand contact 48, contacts 32 and 33, 25, 27 and the single resistant 22 and conductor 26.

When the indicator 51 is at the position designated 2, the contacts will be in the full line position of Figure 6, thus closing an electric circuit and the contact 41, through finger 49, contact 33, contact 27, conductors 28 and 29, resistant elements 23 and 24, bridge 30, contact 31, contact 34 and right hand finger 48.

Greater heat will thus be produced by the two resistant elements 23 and 24 than by the single resistant element 22.

Still greater heat is possible by including all of the resistant elements 22, 23 and 24 in a closed electric circuit through the parts mentioned, by pulling the control element 38 to the dotted line position shown in Figure 6, all of the fingers 48 and 49 being engaged with an adjacent contact 32, 33 and 34 and the latter through

the contacts 25, 27 and 31, and conductors 28, 29 and 30, including all of the resistant elements.

By the anticipated temperature of the weather, one might govern the use of the preferred degree of heat of the three degrees available.

Various changes may be resorted to provided they fall within the spirit and scope of the invention.

We claim as our invention:

1. In combination with a heating chamber in the water cooling system of an engine or the like, electric heating means in said chamber having a core of insulation provided with a projection of insulation disposed exteriorly of the chamber, a support of insulation secured to said projection, and means operable to control the circuit through said electric heating means mounted by said support and projection.

2. Apparatus of the class described having a heating chamber, electric heating means in said chamber having a core of insulation provided with an integral projection disposed longitudinally of the core and exteriorly of the chamber, a support of insulation disposed longitudinally with respect to the core secured to said projection with a part behind and in spaced parallel relation to the projection, co-acting contacts between and mounted by said projection and support, and means to control the position of said contacts mounted on said support.

3. In combination with a heating chamber in the water cooling system of an engine or the like, electric heating means for the water in said chamber having a core provided with a projection disposed exteriorly of the chamber, thermostatic means to control the closing of the circuit through the heating means, a support secured to said projection having a part spaced therefrom, said core and part being of insulation, and means operable to control the degree of heat produced, having contacts disposed between and supported by said support and part.

CHARLES MEYER.
JOSEPH A. MEYER.
